WEIGHT-STEERED WATER SLED

Floyd R. Brown and Walter L. Floehr, Toledo, Ohio, assignors to Unitcast Corporation, Toledo, Ohio, a corporation of Ohio

Filed Jan. 12, 1967, Ser. No. 5,392

Term of patent 14 years

(Cl. D71—1)

FIG. 1

FIG. 2

FIG. 3

FIGURE 1 is a plan view of the weight-steered water sled showing our new design;

FIGURE 2 is a side elevational view of the weight-steered water sled of FIGURE 1; and

FIGURE 3 is a front elevational view of the weight-steered water sled of the preceding figures.

The broken line showings of the outboard motor and the human being are for illustrative purposes only.

We claim:

The ornamental design for a weight-steered water sled, as shown and described.
